UNITED STATES PATENT OFFICE.

SAMUEL JAMES DUNSTAN, OF BARRAPOORT, VICTORIA, AUSTRALIA.

BAG CLOSURE OR MOUTH CLAMP.

1,356,133.

Specification of Letters Patent. Patented Oct. 19, 1920.

Application filed December 24, 1918. Serial No. 268,167.

To all whom it may concern:

Be it known that I, SAMUEL JAMES DUNSTAN, a subject of the King of Great Britain and Ireland, &c., residing at Barrapoort, in the State of Victoria, Commonwealth of Australia, have invented certain new and useful Improvements in Bag Closures or Mouth Clamps; and I do hereby declare the following to be a full, clear, and exact description of the invention, such as will enable others skilled in the art to which it appertains to make and use the same.

To reduce consumption of workers' time, and avoid damage to bags and sacks containing grain or other goods this invention provides an improved bag mouth closure or clamp. One objectionable result of sewing bag mouths in harvest fields, where many bags are filled, is that considerable time must be occupied before the bags are ready to be carted to a silo or other place. Other unsatisfactory results are that when opening the bags by cutting the cords, bags are damaged and cords are wasted.

My clamp can be rapidly applied to a bag, and fastened and can be rapidly removed. It will hold securely, and may be locked, sealed or tied when desired. The same clamps are to be repeatedly used, and will in time save much expense. They consist of jaws and jaw fasteners and are usually of metal, but include any other suitable material. The jaw fasteners include a link which is adjustable to connect the jaws, with a wing nut, screw device, or a spring actuated bolt, or there are modifications described later.

In the accompanying drawings Figure 1 is a plan of a simple clamp with its jaws closed but not fastened, the fastener being a link with a wing nut.

Fig. 2 is a plan showing part of Fig. 1 with the jaws fastened. Fig. 3 shows an end sectional view of the parts in Fig. 2. Fig. 4 shows a sectional view at the other end of the clamp looking in the direction of arrow A in Fig. 1.

Fig. 5 shows the parts in Fig. 3 but with the fastener consisting of a spring actuated bolt, to which may be added at will parts described later.

Fig. 6 is a side view of one end of a clamp

which, instead of being flat, has jaws curved down at each end.

Each clamp shown is reversible and the 55 reversed position is in some cases preferred as when it is desired to have the clamp top smooth, or nearly so.

It is important that during transportation of filled bags the clamp jaws shall not be 60 accidentally unfastened.

To guard against accident or a mistaken partial unfastening it is advisable that if one fastening member be undone, another shall exist and remain fastened until also 65 undone. I provide accordingly.

The clamp has suitable jaws *a*, *b*, of such length as to grip between them the opposite sides or lips of the mouth of the filled bag or sack, while preserving if desired the same 70 width of bag or sack as sewing does, or if desired reducing that width.

These jaws have at one end suitable connecting means, such as a pivot pin *c* passing through an end *b*² of jaw *b* and an end *a*² of jaw *a*. The other ends *a*¹, *b*¹, of the jaws are when required free and widely separated but are adapted to be set close to one another as illustrated, and to be fastened in that position, with the bag ripped between 80 edges or faces of the jaws. Each jaw edge or face (provided to contact with and grip the bag) has preferably projections, as at *f* and *g*, but may have other suitable contour, in some cases being smooth. 85

The space *d* between the closed jaws is of such width that when they are fastened together at their ends *a*¹, *b*¹, that width will suit the thickness occupied by the bag mouth when closed and gripped by the jaws. 90

The fastening means may vary, but I show holes *e*, *e*¹, *e*² in one jaw, and a slot *h* in the other jaw opposite the said holes.

I utilize the slot, and utilize in some cases one of the said holes also. *i* is a suitable 95 (as a U shaped) link pivoted on a bolt or pin *j* passing through slot *h* and slidable along the slot. The pin is fixed to one side of the link and projects through the other side.

The link when in the position of Fig. 1 can be moved toward jaw end *b*¹, and can be swung in the direction of arrow B around jaw end *a*¹, and then slid along the jaws to 100

- the selected position as in Fig. 2. Then a wing nut m (as in Fig. 3) which is on the screw threaded pin or bolt j can be screwed down to press the link i , and as the limbs 5 of the link are somewhat resilient the link will more tightly grip jaw b . I may use a washer or washers between jaw b and the link. When link i holds jaw b tightly it cannot accidentally slip longitudinally, and 10 the use of an extra fastening member to utilize one of the holes e to e^2 will not usually be resorted to. But to provide an extra fastening a hole of jaw a is in Fig. 3 shown screw threaded at a^3 and may be 15 utilized.

The link has holes k which can be set sufficiently in register with a selected hole in jaw a for the introduction when desired of a fastening member.

- 20 I may insert a set screw of any suitable length to engage the part a^3 and one or both holes k ; but it is obvious that either of the holes k could be screw threaded to receive a like set screw.

- 25 The fastening bolt j^1 in Fig. 5 is usable with or without link i ; in the latter case bolt j^1 may be shorter than shown.

The transverse connection or bolt j^1 extends slidably through holes i^1 in link i , and 30 through slot h , and extends across the closed jaws, and its end j^2 passes through a hole k of the link and into a hole of jaw a , and in some cases continues through the other hole k of the link.

- 35 A hole o in bolt end j^2 allows of use of an additional fastening device if desired.

The end j^2 is in some cases as shown screw threaded to enable a nut to be screwed down on link i , or (in the absence of the link) on 40 jaw a .

n is a spring around the stem of bolt j^1 bearing between the bolt head j^3 , and link i or (in the absence of the link) jaw b . Spring n presses strongly and lifts bolt head 45 j^3 and thus keeps end j^2 engaging jaw a , that is holds the clamp closed when required.

To disengage the jaw, bolt head j^3 is moved to compress spring n , and thus move bolt end j^2 clear of jaw a .

- 50 In Fig. 6 b^3 is a curved jaw end, by which a bag ear may be located well above the clamp, grasping of the said ear by a workman would thus be facilitated.

There may be any suitable washers not 55 shown used with my construction.

The user of this invention will in some cases attach one jaw of the clamp at one side of a bag mouth permanently when that is desired to prevent mislaying of the clamp or 60 for any other reason.

Having described this invention, what is claimed by Letters Patent is:—

- 65 1. A bag closure comprising bars pivotally connected at one end, one of said bars being formed adjacent the free end with a

slot, a pivot pin extended through the slot, and a U-shaped member mounted on the pivot pin, said member being of a length to embrace the free end of the other bar, when the pivot pin of the member is at one end of the slot, and held against disengagement on said other bar when the pivot pin of the member is at the opposite end of the slot.

2. A bag closure comprising bars pivotally connected at one end, one of said bars being formed adjacent the free end with a slot, a pivot pin extended through the slot, and a U-shaped member mounted on the pivot pin, said member being of a length to embrace the free end of the other bar, when the pivot pin of the member is at one end of the slot, and held against disengagement on said other bar when the pivot pin of the member is at the opposite end of the slot, and means for securing the pivot pin in any position lengthwise the slot.

3. A bag holder comprising a pair of bars each of which is formed with a serrated edge, one of the bars having a plurality of 90 openings near one end and a single opening near the opposite end, the other bar having a lateral extension at one end formed with an opening which registers with the single opening in the companion bar, the bar with 95 the extension having an elongated slot, a pivot extending through the openings in the bar and extension, a U shape link embracing the bars, the end of the link engaging one of said bars, and a screw extending 100 through the slot and openings formed in the U shape link, which with the link engaging the opposite bar forms a lock, the link having other openings which register with one of the plurality of openings in the bar to 105 receive an additional securing member.

4. A bag closure comprising bars pivotally connected at one end, a loop link slidably and pivotally connected to one bar, the arcuate plane of movement of the free end 110 of the link permitting engagement of such link with the remaining bar, when such link is at one limit of the sliding adjustment thereof and prevent disengagement of such link and bar where the link is at the other 115 limit of such adjustment.

5. A bag holder comprising a pair of substantially parallel bars pivoted together and forming gripping jaws, one of said bars having a longitudinal slot therein, the other 120 of said bars having openings, a U shape link embracing the bars and formed with two pairs of aligned openings which register respectively with one of the openings and the slot in the bars, fastening means extending through the aligned openings in the bar and the link, and locking means extending through the aligned openings in the link and the slot in the bar, and means for securing the link at any desired sliding adjustment. 125 130

6. A bag closure comprising bars pivotally connected together at one end, and means for securing the free ends of the bars together, said means comprising a U-shaped link having the ends thereof mounted for pivotal and longitudinal sliding movement in one of said bars, the sliding movement of the pivot of the link bodily moving the

link lengthwise the bar to a position whereby said link may freely pass over the end of the other bar or to a position where it is prevented by such other bar from passing over the end thereof.

In witness whereof I have hereunto set my hand.

SAMUEL JAMES DUNSTAN.
